UNITED STATES PATENT OFFICE.

OTTO KARCHER, OF CANTON, OHIO, ASSIGNOR OF ONE-HALF TO JOSEPH L. RUSSELL,
OF CANTON, OHIO.

DISPENSING DEVICE.

1,105,797.

Specification of Letters Patent.

Patented Aug. 4, 1914.

Application filed January 23, 1914. Serial No. 813,851.

To all whom it may concern:

Be it known that I, Otto KARCHER, a citizen of the United States, residing at Canton, in the county of Stark and State of Ohio, have invented certain new and useful Improvements in Dispensing Devices, of which the following is a specification.

My invention relates to dispensing devices in which a receptacle is provided to hold a quantity of the article or articles designed to be removed from time to time in small quantities and it further consists in providing tilting means so arranged and constructed that by the tilting of such means a quantity of the article contained in the receptacle may be released.

The objects of the present invention are, first, to provide a device which will be sanitary and convenient, and second, to form a device of the character described that will be simple and of few parts and can be operated in a convenient manner. These objects together with other objects readily apparent to those skilled in the art, I attain by the construction illustrated in the accompanying drawings, although my invention may be embodied in a variety of other mechanical forms, the construction illustrated being chosen by way of example.

In the accompanying drawings—Figure 1 is a perspective view. Fig. 2 is a top view except that the bowl or receptacle is removed. Fig. 3 is a section on line 3—3, Fig. 2 with the addition of the lower portion or part of the bowl or receptacle in proper relative position. Fig. 4 is a view showing two tilting cups in proper relationship with reference to each other, showing one of the cups fully tilted and another cup partially tilted. Fig. 5 is a view showing a portion of the combined bowl or receptacle holding or tilting cup supporting frame. Fig. 6 is a detached view of the detachable partition designed to be located in the receptacle or bowl.

Similar numerals of reference indicate corresponding parts in all the figures of the drawings.

In the accompanying drawings, 1 represents the base to which is attached or formed integral therewith the standard or support 2, said standard or support being formed of a height to hold the various parts carried by the standard in proper elevation to

be easily reached and the movable parts 55 conveniently operated. Upon the top or upper end of the standard or support 2 is attached the bowl or receptacle holding frame 3, which consists of an upright annular flange 4 and the arm 5. The annular 60 flange 4 is formed of a size and shape to fit the bottom or lower part of the bowl or receptacle 6 as best illustrated in Fig. 3, which bowl or receptacle is held in fixed relative position with reference to its support by means of set screws 7 or their equivalents. I have illustrated set screws as one means for holding the bowl or receptacle, but it will be understood that other means may be employed as the only object is to 70 provide some mechanical means to so connect the bowl or receptacle that it will not be easily or accidentally displaced.

The frame or spider 3 is located directly below the opening of the bowl or receptacle 75 6, said frame or spider being for the double purpose of supporting the bowl or receptacle and also carry the tilting cups 8. In the drawings four tilting cups are shown which are substantially duplicates of each other, 80 the construction of each cup being substantially the same and the operation being the same regardless of the number of cups employed and so far as the present invention is concerned a single cup 8 together with 85 its different parts may be employed or any number, reference being had to convenience in handling and due regard being given for the size of the device for the use for which it is intended. For the purpose of providing 90 means for tilting the cup or cups they are provided with the lateral extending lugs 9 which are located upon opposite sides of the cups and in proper alinement with reference to each other, whereby suitable and proper 95 pivotal connection is maintained between said cups and the supporting frame or spider. The frame or spider 3 is provided with the recesses 10, which recesses are preferably formed as shown in Fig. 5 and are so formed 100 to allow the tilting cups 8 to be easily removed, by simply lifting the tilting cups with their bearings upward after which they can be easily removed for any purpose desired.

To the frame or spider 3 are pivotally attached the blades 11, the number of blades 11 corresponding with the number of cups 8 or in other words each cup whether one or

any desired number of cups are employed are to have in connection therewith a blade 11, which blade or blades serve the purpose of preventing the contents of the bowl or receptacle 6 from dropping from the bowl or receptacle during the time the cups are being tilted in either direction. For the purpose of assisting in actuating the blades 11 or turning said blades upon their hinges, 10 said blades are provided with the fingers 12, which fingers are formed of such a length that they will extend over the open portion or portions of the cups 8 and lie upon the inner edge of said cup and upon the top of the 15 frame or spider 3 as best illustrated in Fig. 5. It will be understood that the instant the cups are tilted the fingers 12 will be lifted upward by the upward movement of the portion or portions of the cup or cups upon 20 which the fingers lie, thereby turning the blade or blades upon their pivotal points. The fingers 12 also serve the purpose of agitating the contents of the bowl and preventing any clogging or choking.

25 One of the many uses to which the present invention can be applied is to provide means whereby crackers can be obtained by any number of individuals without in any way handling crackers, except those used by the 30 individual by which arrangement a sanitary device is provided and one that is convenient, economical and perfectly sanitary.

35 The operation of the invention when put to use as above described is substantially as follows: If used in restaurants and like places the device occupies a position similar to an ordinary open top cracker bowl, but it is well understood that regardless to the 40 number of persons desiring crackers each and all can and generally do take from the bowl in their hands, the number of crackers wanted, but in the present instance each individual desiring crackers tilts a tilting cup, the tilting of which delivers in his open 45 hand the crackers contained in said tilting cup. In order to tilt the cup pressure is brought upon the downward extending flange 13, thereby tilting the cup and practically turning the same into substantially the 50 position shown on the left hand side of Fig. 4; after the hand is removed the cup automatically assumes its normal position and is again filled from the crackers contained in the bowl or receptacle. I have described 55 the operation in connection with the dispensing of crackers, to more clearly illustrate the practical and sanitary use of the invention.

60 In some instances it may be desirable that the bowl or receptacle be provided with different compartments, by which arrangement different articles can be placed in the bowl or receptacle without becoming mixed, and the particular article desired easily selected.

65 When it is desired to place different articles

in the bowl a detachable partition is provided, which may be of the form shown in Fig. 6, which may consist of a center bar 14 and the blades 15 arranged as shown, said blades regardless of their number being so formed that they will provide separate and distinct compartments in the bowl or receptacle. It will be understood that the number of partitions may be varied and the same object accomplished as for instance if 75 only two compartments are desired a single partition extending entirely across the bowl will be sufficient.

In addition to the flanges 13 the tilting cups may be provided with pins 16 located 80 near the top of the cups and by a downward pressure upon the pin or pins a tilting action will be imparted to the cups and the article desired released.

85 In order that the contents of the bowl may be seen at all times I prefer to form the bowl or receptacle of glass for the following reasons: First, when formed of glass the bowl will be less liable to become contaminated, and second, it will be transparent, 90 thereby, exposing to view the quantity and contents of whatever material or materials may be located in the bowl or receptacle.

95 The receptacle 6 should be provided with a suitable cover 17, so that the articles contained in the receptacle will be protected from dust and dirt and at the same time be inclosed in such a manner that the articles contained in the receptacle must be taken from the bottom of the receptacle, which receptacle is open upon its bottom portion and is so formed to allow the dispensing cups to be filled from time to time, which filling is brought about by the material in the receptacle dropping into the dispensing cup or 105 cups.

Having fully described my invention what I claim as new and desire to secure by Letters Patent, is—

1. In a dispensing device, the combination 110 of a receptacle, a frame adapted to support and hold said receptacle, a pivoted cup carried by the frame, a blade adapted to close a portion of the cup, said blade provided with a finger, said finger adapted for contact upon the open rim of the cup.

115 2. In a dispensing device of the character described, a receptacle, a frame adapted to support said receptacle, a cup pivotally attached to the receptacle supporting frame, a blade formed of a size less than the top of the pivoted cup and a finger connected to said blade and normally extended over the open portion of the cup.

120 3. In a dispensing device of the character described, a receptacle, a frame adapted to support said receptacle, a cup pivotally attached to the receptacle supporting frame, a blade formed of a size less than the top of the pivoted cup and a finger connected to 130

- said blade and normally extended over the open portion of the cup, said finger and blade adapted to be actuated by the pivotal movement of the cup.
- 5 4. In a dispensing device of the character described, an open bottomed receptacle, a frame adapted to support and hold said receptacle, a series of dispensing cups carried by the receptacle supporting frame, said dispensing cups provided with flanges upon their bottom or under sides, and blades hinged to the receptacle supporting frame and means for actuating said blades.
- 10 5. In a dispensing device of the character described, the combination of an open bottom receptacle, a support adapted to hold said receptacle in relatively fixed position with reference to its support, a series of movable receptacles adapted to receive and hold portions of the contents of the receptacle and means for partially closing said movable cups, and means for actuating said closing means.
- 20 6. In a dispensing device, the combination of a receptacle, a support for said receptacle, a series of open topped dispensing cups pivotally connected to the receptacle support, blades provided with actuating fingers, said

blades adapted to normally close portions of the open topped dispensing cups.

30 7. In a dispensing device, the combination of a receptacle, a support for said receptacle, a series of open topped dispensing cups pivotally connected to the receptacle support, blades provided with actuating fingers, said 35 blades adapted to normally close portions of the open topped dispensing cups, and a detachable partition located within the receptacle.

8. In a dispensing device of the character 40 described, the combination of a receptacle, a supporting frame adapted to hold said receptacle in fixed relative position, a dispensing cup pivotally connected to said receptacle support, a blade hinged to said receptacle support and said blade provided with a finger adapted to actuate said blade and said finger adapted to agitate the contents of the receptacle.

45 In testimony that I claim the above, I 50 have hereunto subscribed my name in the presence of two witnesses.

OTTO KARCHER.
